UNITED STATES PATENT OFFICE.

JAMES CAVANAGH, JR., OF BROCKTON, MASSACHUSETTS, ASSIGNOR TO UNITED SHOE MACF'NERY COMPANY, OF PATERSON, NEW JERSEY, A CORPORATION OF NEW JERSEY.

LASTING-MACHINE.

No. 873,018.

Specification of Letters Patent.

Patented Dec. 10, 1907.

Application filed February 16, 1906. Serial No. 301,449.

To all whom it may concern:

Be it known that I, JAMES CAVANAGH, Jr., a citizen of the United States, residing at Brockton, in the county of Plymouth and 5 Commonwealth of Massachusetts, have invented certain Improvements in Lasting-Machines, of which the following description, in connection with the accompanying drawings, is a specification, like reference 10 characters on the drawings indicating like parts in the several figures.

This invention relates to lasting machines and particularly to the type of lasting machines employed for working a shoe upper over a last and securing it in overworked position by repeated operations of the machine applied to different parts of the shoe. An example of this type of machine is shown in United States Letters Patent No. 584,744, 20 June 15, 1897, and the present invention is herein shown as embodied in a machine of similar general construction. The machine shown in said patent is designed to secure the successively overworked portions of upper temporarily to the innersole of the shoe by means of tacks which are held in a race-way and are taken therefrom by a tack separator which delivers them to a tack carrier having a tack opening or pocket located near 30 its front end. In the operation of the machine shown in that patent the tack carrier is advanced over the edge of the shoe during each complete operation of the machine to present the tack held by it in position to be driven, and a driver is arranged to force the tack from the carrier into the work when the carrier has reached the limit of its movement over the shoe. Preferably also a presser is provided which is actuated inwardly over the portion of overworked upper 35 to be secured and, when working upon Good-year or welt shoes, presses the upper down upon the marginal portion or feather-edge of the innersole and also, as it advances, 40 presses the upper materials inwardly against the shoulder or lip with which the innersole of a welt shoe is provided. The presser thus acts to force the upper materials into the angle of union between the lip and feather-edge 45 of the innersole, in which position it is subsequently secured by stitching which passes through the lip of the innersole, the over-worked upper material, and a superposed welt, as is well understood. The presser 50 above described may be mounted and actu-

ated in any suitable way, but as herein shown it is attached to the lower face of the tack carrier and is advanced and retracted with said carrier. It is desirable that the tack contained in the carrier, which is to be 60 driven through the upper material and into the innersole, be inserted at the angle of union between the feather-edge and the lip of the innersole in order that it may hold the upper material in proper position until it is 65 permanently attached to the lip in a subsequent operation. In order that the tack contained in the pocket of the carrier may be driven in said angle of union, the end of the tack carrier is necessarily somewhat in advance of the presser. The end face of the carrier consequently presses the upper slightly over the lip of the innersole when the carrier is in its most advanced position. In lasting 70 certain portions of the shoe, such as the toe, 75 which require to be plaited for taking care of the fullness of the upper materials, a presser is employed which is shown in the accompanying drawings as a thin plate and will herein be sometimes referred to as the "thin 80 presser" to distinguish it from the presser first described, which is relatively thick and will be sometimes herein designated as the "thick presser".

It is the general practice at the present 85 time to employ wire for binding the upper in overworked position on the toe of welt shoes instead of driving tacks for that purpose. The machine of said Letters Patent has been equipped with means for presenting wire to 90 be used for binding the upper, one form of such wire-presenting means being shown in United States Letters Patent No. 696,740, granted April 1, 1902. Means is also shown in the latter Letters Patent by which the delivery of tacks may be suspended while wire 95 is being used. In the use of the machine thus equipped the wire, which is held under tension, is secured to a tack at one side of the shoe and drawn about the toe of the shoe as 100 the lasting proceeds to bind in overworked position the successively lasted portions of upper material and, finally, is secured to a tack at the opposite side of the shoe. The thin presser above mentioned is employed 105 for pressing the upper material firmly into the angle of union between the lip and feather-edge of the innersole and forms a seat for the wire in the angle between the portion of upper which lies over and is parallel with 110

the feather-edge and that portion which stands up against the side of the lip of the innersole. When the wire has been drawn snugly about the toe it lies securely in this seat and has no tendency to ride up over the lip into a position which would permit the overworked upper to slip back and slacken. The fullness of the upper material at the toe causes its free edge to tend to project outwardly toward the edge of the shoe, thereby increasing the security with which the wire is seated in its holding position.

It is found in practice that the reciprocating tack carrier, which in its tack delivering position extends slightly beyond the outer face of the lip of the innersole, bends the upstanding edge portion of upper material inwardly over the lip and, therefore, tends to lift or straighten up the portion which has been pressed into the angle of union between the lip and feather-edge. This action on the upper displaces the wire slightly from its seat and permits the overworked upper material to slip back so that the toe of the shoe is not as tightly lasted as it should be. In view of this difficulty, and the fact that the tack carrier is not needed while that portion of the shoe is being lasted which is secured by wire instead of tacks, means is provided in accordance with one feature of this invention for discontinuing the movement of the tack carrier into position to engage the upstanding flange of upper material. In the embodiment of the invention herein shown, the movement of the tack carrier is entirely suspended by means under control of the operator. The thick presser, being mounted on the carrier, of course has its movement discontinued when the operation of the tack carrier is suspended. This is advantageous because the thin acting end of the thin presser forms a better seat for the wire when it alone forces the upper material into the angle of union between the lip and feather-edge of the innersole than when the blunt-ended thick presser also acts upon the upper material. The thick presser, however, is more effective than the thin presser in lasting the sides of the shoe and particularly in lasting the heel portion of the shoe, in which the stock to be pressed over the edge of the last is bulky and usually stiff. It will now be understood that the thin presser is needed while the portion of the shoe is being lasted which is secured by wire and that the thick presser and tack carrier are needed while those portions of the shoe are being lasted which are fastened by tacks. Another feature of the invention, therefore, consists in providing means for rendering one of said pressers inoperative when the other presser is operative. Each presser is herein shown as detachably connected with a source of power by which it is operated and means is provided for simultaneously disconnecting one presser from its

operating means when the other presser is connected to its operating means so that the change from one presser to the other is made by a single act of the operator. An incidental advantage which results from moving the tack carrier into its retracted position is that it is thereby located where it does not interfere with the operation of any other parts of the machine. In the normal operation of the machine the tack carrier advances before the grippers of the overworking mechanism release the upper and when lasting the inelastic stock which is frequently found at the toe of the shoe where the upper material includes the toe stiffenings it frequently happens that the grippers, which are yieldingly actuated, occupy a position near enough to the edge of the shoe to be struck and marred by the advancing tack carrier.

In the machine herein shown as embodying the invention the tack separator is arranged to be actuated by mechanism including a part carried by the tack carrier and it of course follows that the movements of the tack separator are stopped and the delivery of tacks to the tack carrier is discontinued when the movement of the tack carrier is suspended.

A further feature of the invention consists in providing means by which a normally operative tack driver may be rendered inoperative while the machine continues in operation for lasting portions of the shoe in which it is not desired to have tacks inserted by the driver. It will be obvious that the driver is not needed while wire is being used instead of tacks for securing the upper in overworked position, and inasmuch as its actuation causes some noise and also wear, as well as vibration of the machine, it is advantageous to render the driver inoperative when tacks are not to be driven. In the machine herein shown the driver is actuated by a cam which raises it against the tension of a spring that imparts to the driver its downward stroke. As illustrated, means is provided under control of the operator for securing the driver in its raised position while portions of the shoe are being lasted which are to be secured by other means than tacks and for releasing the driver again when tacks are to be driven. Preferably the means for rendering the driver operative or inoperative is connected with the means for controlling the operation of the tack carrier and the presser so that the operator may by a single adjustment render the tack carrier, the thick presser, and the driver inoperative and the thin presser operative when it is desired to last a portion of the shoe which is to be secured by wire, and render said driver, tack carrier, and thick presser operative and the thin presser inoperative when the portion of the shoe to be secured by tacks is about to be lasted.

Mechanism is provided in the machine for imparting to the grippers appropriate move-

ments for causing them to plait the upper when the toe of the shoe is being lasted, and as herein shown, this mechanism is connected with the controlling mechanism above mentioned so that it is thrown into operation when the thin presser is operative and is thrown out of operation when the thin presser is inoperative.

In lasting the heel of the shoe the grippers are not employed because the upper is not so supported at the heel portion of the last that it would be stretched if it were pulled by the grippers, and all that is required of the machine is for it to conform the upper material closely to the contour of the sides of the last and to bend it over and secure it to the inner-sole on the bottom of the last. For these purposes the shoe is pressed laterally against an edge rest having a face of sufficiently vertical width to present a substantial bearing for the side of the shoe and the upper material is bent over the edge of the last and pressed into position by the reciprocating thick presser heretofore mentioned. The fullness of upper material bent over the convex edge of the last forms crimps or puckers which it is desirable should be pressed as smooth and flat as possible. It is found in practice that in lasting the heel of a shoe the upper material stands away from the last more or less at the side of the path of the tack carrier toward which the lasting proceeds and that the reciprocating presser does not, for this reason, work the upstanding edge of the material directly inwards as it should do. As a result the upper is sometimes not conformed accurately to the sides of the last at the heel and sometimes an extra fullness of upper material accumulates on the side toward which the lasting proceeds. It is also found that the crimps or puckers are formed between the path followed by the presser in one advance and the path followed by it in its next advance, or between two adjacent tacks. The crimps formed in this position are not pressed down as smoothly as they are when they are located in the path of the presser—as, for example, near the tacks. In view of these conditions I have provided an improved work gage or edge rest which is so formed that it can conform the upper to the contour of a curved side of the last. As herein shown the edge rest is constructed to conform the upper to any contour of the side of the last whether more or less convex or concave, as well as to a straight surface, and it serves to hold the upper snugly against the last at the point adjacent to the advance side of the presser where it has heretofore had a tendency to stand away from the side of the last. The edge rest thus positions the upstanding edge of upper material in conformity with the contour of the side of the last and where it will be bent squarely over the edge of the last by the reciprocating presser.

As shown, the edge rest is provided with a flexible work-engaging head to enable it to adapt itself to the contour of the side of the last. The head of the edge rest may conveniently consist, as illustrated, of two face plates arranged edge to edge and pivotally connected to a support at opposite sides of the line of separation between them. This construction enables the plates to turn independently in conforming to the contour of the work. The pivotal connections between the plates and supports are shown as located near the outer sides of the path of the presser and therefore the rest presents a rigid bearing to the side of the shoe at these two points. When the upper is thus held by the rest the reciprocating presser forces it into desired position and the crimps or puckers are usually formed adjacent to where the tack is driven and are laid very smoothly by the presser.

Another advantage of the improved edge gage is that the pivotal connection of the face plates to the support at points spaced apart enables the adjacent edge of the plates to recede or yield when the work is presented in approximately proper position against them. When a shoe is so presented it is automatically guided to the middle part of the gage and is thus centered with relation to the presser and other working parts of the machine.

These and other features of the invention, including certain details of construction and combinations of parts, will hereinafter be more fully described and pointed out in the claims.

Figure 1 is a side elevation of a lasting machine embodying the present invention. Fig. 2 is a perspective view of certain portions of the machine, including the tack inserting mechanism, with which the present invention is particularly concerned. Fig. 3 is a horizontal section showing in plan view the wire presenting mechanism, the tack carrier, a thin presser and its operating means, and a shoe being operated upon. Fig. 4 is a detail view showing the relation between the tack carrier and the tack separator. Fig. 5 is a perspective view showing a shoe being lasted and a position of the grippers and the thin presser during the lasting operation. Fig. 6 is a sectional view of the toe of a shoe showing the position of the binding wire for holding the upper material in the angle of union between the feather-edge and lip of the innersole. Fig. 7 is a sectional view of a shoe and the tack carrier and thick presser in the position occupied when a tack is about to be driven. Fig. 8 is a plan view of a modified form of thin presser. Fig. 9 is a view of a modified construction for disconnecting the tack carrier actuating cam from the driving shaft. Fig. 10 is a sectional view of said disconnecting mech-

is a shown in Fig. 9. Fig. 11 is a sectional view through the main shaft and the tack carrier operating cam as shown in Fig. 2. Fig. 12 is a detail view of the mechanism for rendering the tack driver inoperative. Fig. 13 is a plan view of a partially lasted heel portion of a shoe, illustrating the position of the unlasted portion of the upper with relation to the side of the last just in advance of the lasted portions of upper. Fig. 14 shows the same portion of shoe shown in Fig. 13 when it is presented against the improved edge rest by which it is conformed to the contour of the side of the last. This figure also shows in dotted lines the advanced position of the thick presser and its effect on the upper. Fig. 15 is a perspective view of the grippers actuating mechanism.

The column A supports the head B in which is mounted the driving shaft D. The shaft supports a cam 280 which has connection through a plate E with a lever 18 fulcrumed at 19 in the frame. The grippers F are suspended from the front end of the lever 18 and are lowered thereby into position for gripping the upper and raised for pulling the upper. The grippers are closed by an arm 28 of a rockshaft 26 which is actuated by a cam 40 on the shaft D. The grippers are guided through a block 47 which is connected to a slide rod 50 provided with a cam roll 54 located in position to be engaged by a cam face 54^a on the rear side of the cam block 40. A spring-actuated arm 50^a presses the slide rod 50 in the direction for holding the cam roll against the cam face 54^a. By the cam and the spring arm, respectively, the pincers are moved toward the machine in approaching their gripping position and moved away from the machine for drawing the upper over the last. The grippers are given other movements for plaiting the upper by mechanism including the rocking segment 57 actuated from a groove in the side of the cam block 40. The construction and the relative arrangement of the grippers and the described mechanism for actuating them to work the upper over the last, may and preferably will be, so far as need be considered in connection with the present invention, the same as in the Letters Patent No. 584,744, before mentioned, and need not be here further described.

A raceway 2 is supplied with tacks from a suitable hopper and the lowermost tack in the raceway groove is removed therefrom by a reciprocating tack separator 4, shown best in Fig. 4. The separator is located above and delivers a tack to a tack carrier 6, which is provided with a pocket to receive the tack. The tack carrier is attached to a sliding bar 84 which moves in suitable guideways in the frame of the machine and at its rear end is connected with a lever 87 which is fulcrumed

at 89 to the machine frame and provided at 65 its upper end with a roll running in the groove of a cam block 88. The cam block imparts to the tack carrier a longitudinal reciprocation from a tack receiving position, shown in Fig. 2, to a tack delivering position, 70 shown in Fig. 7. The tack carrier is provided on its upper face with a plate having an inclined face 7, which, in the reciprocation of the tack carrier, engages a roll on one arm of a lever 9, which, as herein shown, is 75 made in two parts yieldingly connected and fulcrumed at 11, as shown in Fig. 4, to the machine frame. The front end of the arm is provided with a segment rack to engage rack teeth on the tack separator 4, whereby the 80 separator is reciprocated in time relation with the tack carrier and delivers a tack from the raceway when the carrier is in its tack receiving position. A presser 8, herein called the thick presser, for wiping the upper inwardly over the edge of the last and forcing it into the angle of union between the feather edge and lip l of the inner sole, is herein shown (see Fig. 7) as attached to the lower face of the tack carrier to be actuated thereby. The tack carrier necessarily projects somewhat in advance of the presser, as shown, in order to permit the tack held by it to be driven in front of the presser. The driver d, which is operated for driving the 95 tack from the tack pocket into the stock when the tack carrier is in its advanced position, is carried by a driver bar 90. The driver bar is provided with a cam roll for engagement with a cam 91 on the front end of 100 the shaft D, as shown in Fig. 2. The cam is arranged to raise the driver bar and the bar is depressed by a spring 93 which actuates an arm 94 resting on a strut 95 which bears upon the upper end of the driver bar. The 105 devices for actuating the tack carrier and the tack driver are the same as thus far described as those which are shown in detail in the Letters Patent No. 584,744 before mentioned.

In the operation of the machine as thus far described the grippers engage the upper and are uplifted for pulling it over the last and then moved over the last for laying the upper in position to be secured. The tack carrier and the presser 8 are then advanced, the 115 presser forcing the upper material downwardly and inwardly into position to be secured and the tack carrier bringing a tack into position to be driven. The grippers release the upper as the tack carrier advances 120 and the driver cam 91 permits the driver to be depressed by the spring 93 for driving the tack, after which the tack carrier and presser retire and the grippers reengage the upper for another overworking operation. 125 The end face of the tack carrier projecting beyond the presser tends to bend the upper material over the lip of the innersole as may

be seen in Fig. 7, but the upper is forced down into the angle of union between the lip and the feather-edge of the inner sole by the ingoing tack and is there securely held.

5 For lasting the toe portion of the shoe it is necessary to crimp or plait the upper in order to take care of the fullness of upper material worked over the convex edge of the last, and for this purpose the grippers are given plaiting movements as before suggested. The mechanism for giving to the grippers plaiting movements is normally inoperative and is arranged to be rendered operative by means of a knee lever 68 connected 15 to the vertical rock shaft 71, which has a forked arm 73 engaging a sliding collar 74. The collar 74 has connection with an adjusting rod 76 whereby movement of the knee lever in one direction or the other will render 20 operative or inoperative the mechanism for giving to the grippers their plaiting movements, as fully illustrated and described in said Letters Patent No. 584,744.

The machine is provided with a thin presser 25 35 (see Fig. 3) which normally occupies a retracted, inoperative position, but which may be advanced into an operative position for use in lasting the toe of the shoe. The presser is formed on or secured to a bar which 30 is provided at its rear end with a roller to engage a cam plate 23. A spring 21 holds the presser bar normally against the edge of the cam plate which is longitudinally movable and has a notch 38 in its front edge. When 35 the notch is in alignment with the presser bar it permits spring 21 to force the bar into its retracted position. When the cam plate is moved from a position with the notch 38 in alignment with the presser bar to the position 40 shown in Fig. 3 the inclined face of the notch forces the presser bar forward into its operative position. The cam plate is adjusted by means of a connection with an arm 33 of the vertical rockshaft 71 controlled by the knee 45 lever 68. The presser bar is adapted to be reciprocated longitudinally for moving the presser inwardly over the edge of the shoe bottom to force the successively overworked portions of upper into the angle of union between the lip and feather-edge. The actuating 50 means for the presser bar comprises a plunger 42 connected to the lower end of a lever 25 fulcrumed in the machine frame and actuated by a cam face 26^x on the rear side of 55 the cam block 280, as shown in Fig. 1. The head of the plunger 42 plays through a guide-way in a plate 29 which is connected to an arm 45 of the rockshaft 71. The presser bar has a shoulder 43 on its edge adjacent to the plunger 42 with which the head of the plunger is adapted to engage for moving the presser forwardly over the bottom of the shoe. The reverse reciprocatory movement of the 60 presser bar is effected by the spring 21. The

arrangement is such that the head of the 65 plunger 42 is moved by the guide plate 29 into alignment with the shoulder 43 at the same time that the cam plate 23 is actuated for moving the presser bar into its operative position and thereafter, while the presser bar 70 remains in its operative position, it will be reciprocated by the plunger and the spring 21. In practice it is desirable to use the thin presser only while lasting the toe of a shoe and when other portions of a shoe are to be 75 lasted the rock-shaft 71 is turned to put the notch 38 into alignment with the presser bar and to withdraw the head of the plunger 42 from alignment with the shoulder on said bar. The spring 21 thereupon moves the presser 80 into its inoperative position and the plunger reciprocates in a path parallel with the presser bar without actuating the bar.

The machine is herein shown as provided with an abutment or rest 36 formed integral 85 with or secured to a rearwardly extending bar which is provided near its end with a roller adapted to engage the front face of the cam plate 23 and to be adjusted by an inclined face 39 on said cam plate toward and 90 from operative position for resting against the overworked upper material on the outer side of the lip of the innersole, as shown in Figs. 3 and 5.

Instead of the reciprocating thin presser 35 95 the machine may be provided with any other suitable form of presser adapted for forcing the upper into the angle of union between the lip and feather-edge of the innersole—for example, a rotary presser of the general type 100 shown in Fig. 12 may be used if desired. This presser is a thin disk 140 journaled in a lever 142 which is fulcrumed on a stud B^x and provided on its free end with a segment gear engaging a toothed arm 148 secured to the 105 vertical rockshaft 71. The presser 140 will preferably be provided with teeth 143 on its periphery and be turned through an angle corresponding to the distance between one or more teeth during the latter part of, or after, 110 each overworking operation of the grippers. The presser may be turned by a pawl 153 engaging the toothed periphery of the presser and actuated from any moving part of the machine. A pawl 155 may be provided to 115 prevent backward turning movement of the presser. The presser will be moved toward and from operative position by adjustment of the rockshaft 71 and in practice will be advanced into operative position when the 120 mechanism for giving plaiting movements to the grippers is operative and the tack carrier, tack separator, and thick presser are inoperative and will be retracted into inoperative position when the mechanism for giving plaiting 125 movements of the grippers is inoperative and the tack carrier, tack separator, and thick presser are operative. When the

presser occupies its retracted position it will preferably be out of operative relation to its actuating pawl 153.

A reel or spool of wire w is supported on the frame of the machine and the strand of wire passes through suitable tension devices and over a guide finger 40, which is herein shown as secured to and moving with the presser 35, whereby it operates to draw off 10 wire from the reel and present it in proper position to be superimposed upon the successively overworked portions of upper material for binding them in lasted position. The wire is in practice secured to a tack at 15 the side of the shoe, as shown in Figs. 3 and 5, and gradually drawn under tension from the reel by the reciprocating member 40 and, it may be, by the pull of the operator as the 20 lasting proceeds. The reciprocating presser, advancing with each overworking operation of the grippers, forces the upper material into the angle between the lip and feather-edge of the innersole and forms a seat for the wire which binds each overworked portion in position after the grippers release it. When 25 the lasting has proceeded to the opposite side of the shoe from that on which it was begun the tightly drawn wire is fastened to the tack and holds the upper material securely 30 in place. The fullness of the upstanding upper material above the wire causes it to incline outwardly toward the edge of the shoe, as shown most clearly in Fig. 6, so that it overhangs the wire and prevents any tendency of the wire to rise and thereby permit 35 the upper to slip back.

It has been found in practice that the thin presser 35 forces the upper material into position to receive the wire in a satisfactory 40 manner and that the thick presser is not needed when the thin presser is used. The thick presser, however, is best adapted by reason of its form and its greater strength for pressing the upper materials into lasted position at the sides and especially at the heel of the shoe. It is also found that the movement of the tack carrier into its advanced position when the upper material is being secured by wire is attended by certain disadvantages. The most important disadvantage is that the tack carrier advances as heretofore explained to a position in which its front edge contacts with the upstanding upper material on the outer side of the lip of the 55 innersole and bends the upper material over the lip. This bending of the upper material tends to pull it out of the angle between the feather-edge and lip of the innersole and to unseat the wire so that the wire holds the upper less securely and sometimes permits it to 60 slip back toward the edge of the last so that the shoe is not lasted as tightly as it should be. Another disadvantage incident to the continued movement of the tack carrier and

thick presser at times when they are not 65 needed is that useless wear of the moving parts is occasioned thereby. In accordance with another feature of this invention means is provided for preventing the tack carrier from advancing into a position where it tends 70 to displace the overworked upper materials, and, as herein shown, this means consists in mechanism for disconnecting the tack carrier and thick presser from their driving mechanism. While this may be accomplished in various ways, the machine herein illustrated is provided with means for disconnecting the cam 88 from the driving shaft D. The cam 88 is shown as loose on the driving shaft and in the construction illustrated in Figs. 2 and 80 11 is provided with a device shown as a pivoted, spring-pressed latch 10^x adapted to engage with a notch in a collar 12 which is secured to the driving shaft. When the latch is seated in the notch of said collar the cam 85 88 is rotated with the shaft and the tack carrier and thick presser are reciprocated, as has been described. For the purpose of disconnecting the cam from the driving shaft means is provided for withdrawing the latch 90 from the notch in the collar 12 and preferably for arresting the cam 88 at a point in its rotation at which the tack carrier and thick presser occupy their retracted positions. To this end the vertical rock-shaft 71 is herein 95 shown as provided with an arm to which is attached a combined disconnecting device and brake arranged to be moved into and out of the path of the heel portion 13 of the latch 10^x. When the device 14 is moved 100 into the path of said heel portion the latch engages it at a time in the rotation of the cam when the tack carrier and thick presser are in their retracted position and is rocked to disengage itself from the notch in the continuously rotating collar 12. The device 14 serves by its frictional engagement with the spring-pressed latch to stop the rotation of the cam 88 immediately after said cam has been disconnected from the collar on the 110 driving shaft.

A modified construction of mechanism for disconnecting cam 88 from the driving shaft D is shown in Figs. 9 and 10. In this construction the cam is provided with a spring-pressed pin 15 adapted to enter a suitably formed pin hole in the collar 12 for normally connecting the cam to the driving shaft. The pin 15 has a stud 16 which moves in a slot in the periphery of the cam and is adapted for engagement with a combined disconnecting device and brake 17, shown as mounted on a rockshaft 18, which in practice will be supported in bearings in the frame B. The rockshaft is provided with a 120 segment gear 19 in engagement with a segment on an arm 20 secured to the vertical rockshaft 71. Movement of the vertical 125

rockshaft in one direction will throw the disconnecting device and brake 17 into the path of the stud 16 so that as the stud moves with the rotating cam it will engage the inclined face of the device 17 and be moved to the right, thereby withdrawing the pin 15 from engagement with the collar 12. The thick end of the tapering portion of the device 17 acts as a brake and arrests the rotation of the cam so that the tack carrier is stopped in its retracted position.

The devices for disconnecting the cam 88 from the driving shaft are preferably arranged on the rockshaft 71 in such angular position with relation to the devices which control the movements of the thin presser and the plaiting mechanism that the tack carrier, thick presser and the tack separator will be rendered inoperative when the thin presser and the plaiting mechanism are rendered operative.

The operation of the tack driver during the period when wire is being employed instead of tacks for securing the upper in over-worked position is unnecessary and not only causes useless wear, but occasions noise which it is desirable to discontinue. The machine is, therefore, provided with means for rendering the driver inoperative while those portions of the shoe which are secured by wire are being lasted, and, as herein illustrated, this is done without interrupting the operation of the driver actuating cam. In the machine shown a latch 21 is arranged to engage the driver bar and hold the latter at substantially the limit of the upward movement imparted to it by the cam 91. The driver bar is shown as provided with a notch 22 which receives an inwardly projecting end of the latch 21. The latch is shown as mounted loosely on a shaft 24 and acted upon by a spring 27 for swinging it in the direction to engage the notch on the driver bar. The rockshaft 24 is provided with a fixed collar 28 having a shoulder to engage with a stud 29 on the latch. The rockshaft also has a second collar 30 having an arm to which is pivotally connected a link 31 extending to an arm 32 on the vertical rockshaft 71. The arm 32 is secured to the rockshaft in such angular relation to the devices for disconnecting the tack carrier, the tack separator, and the thick presser from their driving mechanism and the devices for controlling the movement of the thin presser and the plaiting mechanism that the latch is held out of position for engaging the driver when the tack block and the tack separator are operative for presenting tacks to be driven. The position of the arm 32 on the rockshaft 71 is such as to permit the latch 21 to engage the driver and render it inoperative when the tack carrier and tack separator are rendered inoperative. It is to be noted that the latch 21 is yieldingly actuated into

position to engage the driver so that it presents no obstacle to the movement of the rockshaft 71 at any point in the cycle of operations of the machine. It will also be observed that the device 14 may be moved at any time during the cycle of operations of the machine into position to coöperate with the latch 10^x for disengaging the cam 88 from the driving shaft.

The novel edge rest against which the side or edge of the shoe is presented during the lasting operation comprises a pivotally mounted carrier arm 10 upon which is supported a flexible work-engaging head, as illustrated in Fig. 14. As herein shown, the work-engaging head comprises two face plates 41 pivoted at 45 near their adjacent edges to the front end of the arm 10. The plates each have a limited amount of free movement about their pivots, their movement in one direction being limited by contact of their adjacent ends with the end of the arm 10 and their movement in the opposite direction being limited by stops 46. This construction of the edge rest enables it to present an approximately uniform bearing against convex, concave, or straight portions of the side of a last and is particularly useful when lasting the heel of a shoe where the upper requires to be conformed by the edge rest to the convex contour of the side of the last. The edge rest constructed as shown presses the upper against the side of the last at the advance side of the path of the reciprocating presser where it normally tends to stand back from the last. The rest thus holds the upper in proper position to be acted upon by the presser and forced squarely inward and fulled or crimped. The pivotal connections of the plates 41 to the supporting arm at points spaced apart as shown insure the presentation and pressure of the shoe always against the central portion of the gage and therefore in predetermined relation to the gage and to the working parts of the machine.

In the operation of the machine, the heel and sides of the shoe will be lasted in the usual manner, the shoe being held in the hands of the operator or supported by a jack if desired and pressed against the edge rest, the acting face of which will adapt itself to the contour of the different portions of the shoe presented to it. After the upper has been worked over the last and secured by tacks to the innersole on the sides and heel, tacks will be inserted partially into the shoe bottom at opposite sides of the toe, and the machine will be stopped to permit the operator to secure the end of the binding wire to one of the tacks. Before re-starting the machine the operator will shift the knee lever to turn the rockshaft 71 in the direction to disconnect the cam 88 from the actuating shaft D, to permit the latch 21 to engage the driver

bar 90, to move the cam plate 23 for forcing the thin presser into its operative position and to put the plunger 42 into position to actuate said thin presser, and also to render 5 operative the mechanism for giving plaiting movements to the grippers. All these adjustments having been effected by a single movement of the rockshaft, as before explained, the machine is re-started and there- 10 after the successively overworked portions of upper material are forced into the angle of union between the lip and feather-edge of the innersole by the thin presser and are bound in lasted position about the toe of the 15 shoe by the wire w. When the lasting of the toe is completed the machine will be stopped and the wire will be secured to the tack on the side where the lasting operation is ended. The knee lever will then be shifted to turn 20 the rockshaft 71 in the direction for restoring to their former positions the parts previously adjusted by it, and the machine is then ready for lasting the sides and heel of another shoe. Having explained the nature of the invention 25 and described a construction embodying it in one of the best forms now known to me, I claim as new and desire to secure by Letters Patent of the United States:—

1. In a lasting machine, the combination 30 with means for working an upper over a last, of means including a movable carrier for supplying fastening material in position to be inserted to secure the upper in overworked position, means for causing the insertion of 35 the fastening material, and means for suspending the operation of said carrier while the overworking means continues in operation.

2. In a lasting machine, the combination 40 with means for working an upper over a last, of means including a tack carrier for supplying tacks in position to be driven to secure the upper in overworked position, a driver, and means for suspending the operation of 45 the tack carrier while the overworking means continues in operation.

3. In a lasting machine, the combination 50 with grippers and means for actuating the grippers to work an upper over a last, of means for supplying tacks, a driver, and means for simultaneously rendering the tack supplying means and the driver inoperative while the grippers continue in operation for working the upper over the last.

55 4. In a lasting machine, the combination with means for working an upper over a last, of means for pressing the overworked portion of upper into position to be secured and for delivering tacks in position to be driven, and means for rendering inoperative said pressing and tack delivering means while the overworking means continues in operation.

5. In a lasting machine, a thick presser for 60 forcing the upper into position to be secured, and a thin presser for forcing the upper into

position to be secured, actuating means for said pressers, and means under control of the operator for rendering either of said pressers operative or inoperative at will.

6. In a lasting machine, a thick presser for 70 forcing the upper into position to be secured, and a thin presser for forcing the upper into position to be secured, actuating means for said pressers, and means under control of the operator for rendering the thick presser in- 75 operative when the thin presser is operative.

7. In a lasting machine, the combination 80 with means for working an upper over a last, of means for pressing the upper into suitable position to be secured by wire, other means for pressing the upper into a different position to be secured by tacks, and means under control of the operator for rendering either of said pressing means operative or inoperative at will.

8. In a lasting machine, the combination 85 with means for working an upper over a last, a tack raceway, a tack separator, a tack driver, means for pressing the upper into position to be secured by tacks, and means 90 for pressing the upper into position to be secured by wire, of means for rendering inoperative the tack separator and the first-mentioned presser when the other presser is operative.

9. In a lasting machine, mechanism for working an upper over a last, means arranged to be rendered operative or inoperative for supplying fastening material, means for pressing the upper into position to be secured, and mechanism for simultaneously rendering one of said means inoperative and the other means operative.

10. In a lasting machine, means for working an upper over a last, means for supplying fastenings, a driver, a presser arranged to be rendered operative or inoperative, and means under control of the operator for rendering the driver inoperative and the presser operative.

11. In a lasting machine, means for working an upper over a last, including means adapted to be rendered operative or inoperative for plaiting the upper, mechanism for supplying and inserting fastenings to secure 115 the upper in overworked position, and means under control of the operator for simultaneously rendering the plaiting means operative and rendering the mechanism for supplying and inserting fastenings inoperative.

12. In a lasting machine, means for working an upper over a last, including means adapted to be rendered operative or inoperative for plaiting the upper, mechanism, including a driver, for supplying and inserting 125 fastenings, and means for rendering the driver inoperative while the plaiting means is plaiting the upper.

13. In a lasting machine, means for working an upper over a last, including means ar- 130

ranged to be rendered operative or inoperative for plaiting the upper, means for inserting fastenings, and means for rendering the fastening inserting means inoperative while the overworking means continues in operation for plaiting the upper.

14. In a lasting machine, means for working an upper over a last, including means arranged to be rendered operative or inoperative for plaiting the upper, and a presser for forcing the overworked upper into position to receive a fastening, and means under control of the operator for rendering said presser inoperative when the plaiting means is rendered operative.

15. In a lasting machine, the combination with grippers and means to actuate them for working an upper over a last, including means adapted to be rendered operative at times for causing the grippers to plait the upper, of a normally operative presser, a second presser, and means for rendering said normally operative presser inoperative and the second presser operative when the mechanism for causing the grippers to plait the upper is rendered operative.

16. In a lasting machine, the combination with means for working an upper over a last, of means for supplying tacks, means for presenting wire, a plurality of pressers, and means for rendering one presser operative when the means for supplying tacks is operative and for rendering said last-mentioned presser inoperative and another presser operative when the means for presenting wire is operative.

17. In a machine of the class described, means for supplying different kinds of fastening material, a plurality of pressers, means under control of the operator for determining the kind of fastening material to be supplied, and means whereby one presser is rendered operative when one kind of fastening material is being supplied and another presser is rendered operative when a different kind of fastening material is being supplied.

18. In a lasting machine, the combination with means for working an upper over a last, of means for supplying different kinds of fastening material, a plurality of pressers of different formation adapted to force the upper into position to receive the fastening material, and means for causing one presser to be rendered operative when one kind of fastening material is being supplied and another presser to be rendered operative when a different kind of fastening material is being supplied.

19. In a lasting machine, the combination with means for working an upper over a last, of means, including a movable carrier, for supplying fastening material in position to be inserted, a continuously moving actuator to which said carrier is normally connected, and means under control of the operator for dis-

connecting said carrier from the continuously moving actuator while the overworking means continues in operation.

20. In a lasting machine, the combination with means for working an upper over a last, of a driver operatively connected thereto and actuated in time relation with the overworking means for inserting tacks to secure the upper in overworked position, and means under control of the operator for suspending the operations of the driver while the first-mentioned means continues to operate for working an upper over a last.

21. In a machine of the class described, the combination with a driver and means, including a movable carrier, for supplying fastening material in position to be inserted, of an actuator for the driver and the carrier, and means under control of the operator for rendering the driver and carrier inoperative while the actuator continues in operation.

22. In a machine for lasting shoes, the combination with means for working an upper over a last, of means, including a driver, for inserting fastenings in time relation with the overworking operations, and means for suspending the operations of the driver during repeated operations of the overworking means upon a shoe.

23. In a lasting machine, means for working an upper over a last, means, including a driver, for supplying and inserting fastenings, means arranged to be rendered operative or inoperative for presenting wire, and means for rendering the driver inoperative while the wire presenting means continues in operation.

24. In a lasting machine, means for working an upper over a last, a driver, and means for actuating the driver combined with mechanism for suspending the operation of the driver, comprising a pivoted latch, a stop face on the driver to be engaged by the latch, means for yieldingly pressing the latch toward the driver, and means under control of the operator for normally holding the latch out of engagement with the stop face on the driver.

25. In a machine of the class described, an edge rest comprising a support and a plurality of plates pivotally connected to the support near their adjacent edges to permit them to move relatively for adapting the work-engaging face of the rest to the contour of the work.

26. In a machine of the class described, an edge rest having a work-engaging head comprising two plates arranged edge to edge and pivotally supported near their adjacent edges to permit relative movement for presenting a concave or a convex acting face.

27. In a machine of the class described, an edge rest presenting a firm bearing to the work at either side of the middle of the gage and a yielding bearing at the middle of the

gage whereby the gage tends to center the work pressed against it.

28. In a machine of the class described, the combination with a presser for forcing upper material over the edge of a last, of an edge rest having an acting face adapted to conform to the convex side of the heel end of the last and hold the upper material against the side of the last at the advance side of the 10 presser.

29. In a machine for working an upper over a last progressively by repeated operations of the machine applied to different parts successively, the combination with a 15 reciprocating presser, of an edge rest having a flexible acting face and arranged to hold the upper material against the side of the

heel end of the last at the side of the presser toward which the lasting is advancing.

30. In a lasting machine, the combination 20 with means for working an upper over a last, of a presser adapted to be rendered operative or inoperative, a tack supplying and inserting means, and manually controlled means for rendering the tack supplying and inserting means inoperative when the presser is rendered operative.

In testimony whereof I have signed my name to this specification in the presence of two subscribing witnesses.
